[57] CLAIM

The ornamental design for a hemispherical pager, as shown and described.

DESCRIPTION

FIG. 1 is a front elevational view of a hemispherical pager showing my new design, the rear being unornamented;

FIG. 2 is a left side elevational view;

FIG. 3 is a top view thereof; and,

FIG. 4 is a right side elevational view thereof.

The bottom view of the hemispherical pager forms no part of the claimed design.

The broken line showing a clip in FIGS. 2-4 is for illustrative purposes only and forms no part of the claimed design.
